HAROLD C. SUCKERT, OF NEW YORK, N. Y.

VACUUM FUEL-FEEDING SYSTEM.

1,162,819.

Specification of Letters Patent.

Patented Dec. 7, 1915.

Application filed March 11, 1915. Serial No. 13,781.

To all whom it may concern:

Be it known that I, HAROLD C. SUCKERT, a citizen of the United States, and a resident of the borough of Manhattan, city, county, and State of New York, have invented certain new and useful Improvements in Vacuum Fuel-Feeding Systems for Gasoline-Engines, of which the following is a specification.

- 10 In the installation of gasoline engines it has heretofore been the almost universal practice to place the gasoline or fuel tank above the carburetor in order to secure a gravity feed of the fuel from the tank to the carburetor. In the few instances in which the fuel tank has been placed below the carburetor some form of pump has been used to maintain an air pressure in the gasoline tank in order to force the gasoline up 20 to the carburetor. In other cases a vacuum pump has been used to draw the gasoline from the fuel tank to a point higher than the carburetor and to then feed the gasoline by gravity to the carburetor.

25 This invention relates to this latter type of fuel feeding means.

It is the main object of this invention to simplify the vacuum apparatus by means of which the gasoline is drawn from the tank 30 and delivered into the small gravity tank from which it is fed to the carburetor.

Another object of the invention is to dispense with all float-operated devices and to provide an apparatus which will be very 35 simple in construction and positive and reliable in operation.

Other objects and advantages of the invention will appear hereinafter.

In the drawings, Figure 1 is an outline 40 view of my improved fuel feeding system applied to a gasoline engine; Fig. 2 is a vertical central sectional view of the vacuum pump and gravity feeding tank, showing the parts in the position which they occupy 45 when gasoline is being drawn from the storage tank into the pumping chamber; and Fig. 3 a similar view showing the parts in the position which they occupy when the gasoline is being delivered from the pumping chamber into the gravity feed tank, the pumping chamber being cut off from communication with the suction apparatus.

50 Referring to the various parts by numerals, 1 designates the engine, 2 the manifold through which the gas from the carburetor is connected to the engine intake; 3 the car-

buretor and 4 the fuel tank. The gravity feed tank 5 is located in any convenient position above the carburetor, preferably under the hood of the engine, as indicated in Fig. 60 1. The lower end of this gravity feed tank is connected by a pipe 6 to the carburetor and through this pipe fuel is fed by gravity. The fuel tank 4 is connected to the pumping apparatus through a pipe 7 and said apparatus is connected to the manifold of the engine through a pipe 8.

Extending vertically and centrally through the gravity feed tank 5 is a rigid spindle 9. Mounted on this spindle near the upper end 70 thereof is the pumping chamber 10, said chamber being formed with a sleeve 11 at its upper end, said sleeve fitting snugly and sliding on the upper part of the spindle. The lower end of the pumping chamber is 75 provided with a collar 12 which slides on the lower portion of the spindle, the upper end of said collar being adapted to contact with a shoulder 13 on the spindle to limit the upward movement of the pumping chamber. 80 The upper portion of the spindle is formed with two vertical passages 14 and 15, the passage 14 being connected to the suction pipe 8 which leads to the manifold of the engine, and the passage 15 being connected 85 with the supply pipe 7 which leads to the fuel tank. The lower ends of these passages 14 and 15 are in communication with the interior of the pumping chamber 10 through ports 16 and 17 respectively. When the 90 pumping chamber 10 is in its upper position the lower end of the sleeve 11 is above said ports 16 and 17 so that said ports are uncovered, as shown in Fig. 2. The spindle 9 is formed with a valve seat 18 below the 95 ports 16 and 17, and the lower end of the sleeve 11 is shaped to fit said seat when the pumping chamber is in its lower position, as shown in Fig. 3. In this position of the pumping chamber the ports 16 and 17 are 100 closed.

Below the shoulder 13 the spindle 9 is provided with the vertical passage 19; the upper transverse ports 20 and the lower transverse ports 21. When the pumping 105 chamber is in its upper position as shown in Fig. 2, ports 20 are closed by the collar 12; and when the pumping chamber is in its lower position said ports are in open communication with the interior of the pumping chamber so that the interior of the gravity feed tank 5 is in communication with the 110

interior of the pumping chamber through ports 21, passage 19 and ports 20, as shown in Fig. 3. The spindle 9 at its lower end is provided with the vertical passage 22, the 5 inlet ports 23 placing the interior of the gravity feed tank in communication with the passage 22, and this latter passage is in communication with the feed pipe 6 which leads to the carbureter.

10 The collar 12 is horizontally bored to receive springs 24, and said springs yieldingly hold ball catches 25 in recesses 26 formed in the spindle 9. Surrounding the spindle 9 between the collar 12 and the bottom 15 of the gravity feed tank is a spring 27, said spring normally supporting the pumping chamber 10 in its upper position. There are two sets of recesses 26 one above the other and the ball catches 25 engage the 20 upper set when the pumping chamber is in its upper position, and engage the lower set when the pumping chamber is in its lower position, as shown respectively in Figs. 2 and 3 of the drawing. The spring 27 is of 25 such tension that it will lift the chamber 10 to its upper position when said chamber is empty or substantially so.

The operation of the apparatus may be 30 briefly described as follows: When the engine is in operation there will be sufficient suction through pipe 8 to exhaust air from the pumping chamber 10. This will result in a suction through pipe 7 sufficient to lift the 35 gasoline from the fuel tank 4 into the pumping chamber through passage 15 and port 17. This operation will continue, while the engine is running, until sufficient gasoline has been accumulated in the chamber 10 to overcome the friction of the ball catches 40 25 and the tension of the spring 27. The pumping chamber will then move downwardly, closing ports 16 and 17 and uncovering ports 20. When the ball catches reach the lower notches 26 the tension of the 45 spring 27 will be sufficient to hold the chamber 10 in that position when the ball catches have snapped into the said lower notches. The fuel will then flow from chamber 10 through ports 20, passage 19 and ports 21 50 into the gravity feeding tank. When the chamber 10 is empty, or substantially so, the spring 27 will overcome the friction of the ball catches 25 and move the chamber 10 back to its upper position, thereby uncovering ports 16 and 17 and closing ports 55 20. The gasoline from the feed tank 5 will flow through ports 23, passage 22 and pipe 6 to the carbureter. Passage 15 is in communication with the interior of the feed 60 tank through a relief port 28, and said tank is in communication with the atmosphere through a relief port 29. In the passage 14, is arranged an inwardly seating valve 30, the purpose of which is to maintain in a 65 pumping chamber any vacuum produced

therein, while at the same time permitting air from said chamber to be readily exhausted through pipe 8. The port 28 permits air to flow into pipe 7 so that gasoline therein may flow back to the fuel tank; and port 29 prevents the accumulation of any pressure or the building up of a vacuum in the feed tank.

From the foregoing it is manifest that I provide a very simple suction-operated apparatus by which the gasoline or other liquid fuel may be lifted from the fuel tank into the gravity feed chamber 5 from which it may be conducted to the carbureter. The chamber 10 serves in the nature of a pumping chamber and also serves as a means for limiting the amount of gasoline which may be accumulated in the tank 5. It is manifest that if the supply of gasoline in the tank 5 prevents the emptying of the chamber 10 the 75 80 85 said chamber 10 will remain in its lower position, thereby cutting off the exhausting apparatus from the interior of said chamber. This, of course, prevents the further accumulation of gasoline until the supply in the tank 5 has been sufficiently reduced. When gasoline accumulates in tank 5 sufficiently to seal the ports 21 no further air can pass upwardly through said ports into the chamber 10. These ports are therefore sealed and will remain so until gasoline is used from tank 5 sufficiently to unseal said ports. As soon as said ports are unsealed there will be a further flow of gasoline from the chamber 10 sufficient to seal them. 90 95 100 This operation will continue until the supply of gasoline in chamber 10 is exhausted, or substantially so, when said chamber will be returned to its upper normal position.

It will, of course, be understood that the 105 construction of the apparatus may be modified to a considerable extent without departing from the scope of the invention and I desire it understood that I am not to be limited in the matter of details of construction and specific arrangements of parts.

What I claim is:

1. A fuel feeding apparatus comprising a fuel tank, a carbureter, a gasoline engine and a manifold connected with the intake 115 ports of the engine, of a feed tank above the carbureter, a vertically movable pumping chamber in said feed tank, means connecting the interior of said pumping chamber with the manifold, means connecting the interior of said chamber with the fuel tank, means connecting the lower end of the feed tank with the carbureter, and means whereby a predetermined amount of gasoline in the pumping chamber will move said 120 125 chamber to close communication with the fuel tank and the manifold and will open communication between said pumping chamber and the interior of the feed tank.

2. A fuel feeding apparatus comprising a 130

feed tank, a vertically movable pumping chamber therein, a fuel inlet into the interior of said pumping chamber, an exhaust outlet from the interior of said pumping chamber, means whereby the accumulation of gasoline in the pumping chamber will move said chamber to close the fuel inlet and the exhaust outlet and will open communication between the interior of the pumping chamber and the feed tank, the feed tank being provided with an outlet port at its lower end.

3. A fuel feeding apparatus comprising a feed tank, a vertically movable pumping chamber therein, a fuel inlet into the interior of said pumping chamber, an exhaust outlet from the interior of said pumping chamber, means for normally holding the pumping chamber in communication with the fuel inlet and the exhaust outlet, and means whereby the accumulation of gasoline in the pumping chamber will move said chamber to close the fuel inlet and the exhaust outlet and will open communication between the interior of the pumping chamber and the feed tank, the feed tank being provided with an outlet port at its lower end.

4. A fuel feeding apparatus comprising a feed tank, a vertically movable pumping chamber therein, a fuel inlet into the interior of said pumping chamber, an exhaust outlet from the interior of said pumping chamber, means for normally holding the pumping chamber in communication with the fuel inlet and the exhaust outlet, and means whereby the accumulation of gasoline in the pumping chamber will move said chamber to close the exhaust outlet and will open communication between the interior of the pumping chamber and the feed tank, the feed tank being provided with an outlet port at its lower end.

5. A fuel feeding apparatus comprising a feed tank, a vertically movable pumping chamber therein, a fuel inlet into the interior of said pumping chamber, an exhaust outlet from the interior of said pumping chamber, means for normally holding the pumping chamber in communication with the fuel inlet and the exhaust outlet, means whereby the accumulation of gasoline in the pumping chamber will move said chamber to close the exhaust outlet and will open communication between the interior of the pumping chamber and the feed tank, the feed tank being provided with an outlet port at its lower end, and means for moving the pumping chamber to restore communication between the interior of said chamber and the exhaust outlet and to close communication between the pumping chamber and the feed tank when fluid has been discharged from the pumping chamber into the feed tank.

6. A fuel feeding apparatus comprising a feed tank, a vertically movable pumping chamber therein, a fuel inlet into the interior of said pumping chamber, an exhaust outlet from the interior of said pumping chamber, means for normally holding the pumping chamber in communication with the fuel inlet and the exhaust outlet, means whereby the accumulation of gasoline in the pumping chamber will move said chamber to close the fuel inlet and the exhaust outlet and will open communication between the interior of the pumping chamber and the feed tank, the feed tank being provided with an outlet port at its lower end, and means for moving the pumping chamber to restore communication between the interior of said chamber and the exhaust outlet and to close communication between the pumping chamber and the feed tank when fluid has been discharged from the pumping chamber into the feed tank.

7. The combination of a feed tank, a reciprocable valve mechanism therein, suction-operated means for accumulating fluid in said valve apparatus, means whereby a predetermined accumulation of fluid will move said fluid and said valve apparatus downwardly and cut off communication with the suction-operated means and open communication between said valve apparatus and the feed tank to permit the discharge of the accumulated fluid into the feed tank, and means for moving the valve apparatus upwardly to its normal position.

8. The combination of a feed tank, a reciprocable valve mechanism, suction-operated means for accumulating fluid in said valve apparatus, means whereby a predetermined accumulation of fluid will move said fluid and said valve apparatus downwardly and cut off communication with the suction-operated means and open communication between said valve apparatus and the feed tank to permit the discharge of the accumulated fluid into the feed tank, and means for moving the valve apparatus upwardly to its normal position.

9. The combination of a feed tank, a vertically movable pumping chamber therein, a fluid inlet connected to the interior of the pumping chamber, an exhaust outlet leading from the interior of said chamber, yieldable means for holding the pumping chamber in communication with the fluid inlet and the exhaust outlet, means whereby the weight of the accumulated fluid in the pumping chamber will depress said chamber and close communication between said chamber and the exhaust outlet and open communication between said chamber and the feed tank, and means for raising the pumping chamber after the discharge of fluid to restore communication between said chamber and the fluid inlet and the exhaust outlet.

10. The combination of a feed tank, a vertically movable pumping chamber therein, a longitudinally extending spindle in the feed tank and supporting the pumping chamber, said spindle being formed with two ports leading into the interior of the pumping chamber, and with ports connecting the interior of the pumping chamber with the interior of the feed tank when the pumping chamber is in its lower position, and also with ports leading into the bottom of the feed tank, a valve to close the ports leading into the pumping chamber when the pumping chamber is in its lower position, and yieldable means for holding the pumping chamber in its upper position.

11. The combination of a feed tank, a vertical central spindle therein, a reciprocable pumping chamber mounted on said spindle, a spring normally holding said pumping chamber in its upper position, yieldable means carried by the pumping

chamber to engage the spindle to assist in holding said pumping chamber in its upper position, a pair of ports leading into the pumping chamber near its upper end when the chamber is in its upper position, ports formed in the spindle and connecting the lower end of the pumping chamber with the feed tank when the pumping chamber is in its lower position, a valve closing communication between the upper end of the pumping chamber and the ports in the spindle when the pumping chamber is in its lower position, and means for restoring the pumping chamber to its upper position when the fluid therein has been discharged into the feed tank.

In testimony whereof I hereunto affix my signature in the presence of two witnesses.

HAROLD C. SUCKERT.
